COMBINED CRYSTAL AND BEZEL FOR A WATCH

Henry A. Federman, 200 Central Park S.,
New York, N.Y.

Filed July 6, 1964, Ser. No. 80,713

Term of patent 14 years

(Cl. D42—8)

Fig. 1.

Fig. 2.

Fig. 4

Fig. 3.

Fig. 6.

Fig. 5.

FIG. 1 is a top plan view of a combined crystal and bezel for a watch showing my new design;

FIG. 2 is a side elevational view thereof, on a reduced scale;

FIG. 3 is a side elevational view of a modified embodiment of my combined crystal and bezel for a watch and drawn to the same scale as FIG. 2.

FIG. 4 is a cross-sectional view of the same scale as FIG. 1 of the embodiment shown in FIG. 2;

FIG. 5 is a bottom plan view of the bezel alone; and

FIG. 6 is a partial cross-sectional view of the embodiment shown in FIG. 3.

Except for the dash and dot lines 4—4 in FIG. 1 and in the upper left of FIG. 6, all other showings by dash and dot lines in the drawings are included solely for illustration.

The fragmentary, broken-line showings of a watch body and wrist strap are for illustrative purposes only.

This application is a continuation-in-part of my pending application Serial No. D. 75,852 filed July 17, 1963 and now abandoned.

I claim:

The ornamental design for a combined crystal and bezel for a watch, as shown and described.
